(57) **CLAIM**

What is claimed is the ornamental design for a display screen with graphical user interface, as shown and described.

DESCRIPTION

FIG. 1 is a front view of a display screen with graphical user interface, showing a first embodiment of the new design. FIG. 2 is a front view of a second embodiment thereof; FIG. 3 is a front view of a third embodiment thereof; FIG. 4 is a front view of a fourth embodiment thereof; FIG. 5 is a front view of a fifth embodiment thereof; and, FIG. 6 is a front view of a sixth embodiment thereof. The broken line rectangle shows the display screen. All broken lines outside the rectangle show a device. All broken lines inside of the rectangle show portions of the graphical user interface. None of the aforementioned broken lines form part of the claimed design.
